UNITED STATES PATENT OFFICE.

JOSIAH H. ROHRER, OF PHILADELPHIA, PENNSYLVANIA.

AIR HEATER.

Application filed December 12, 1925. Serial No. 75,033.

Economy in the combustion of fuel is the aim of all designers of boilers and heaters for commercial purposes. Efficiency in boiler construction is attained by the utilization of as much of the heat generated by the combustion of fuel as it is possible to use. All the heat contained in the products of combustion, when discharged in the atmosphere, is lost. It is one object of my invention to provide a device by the operation of which the heat in the products of combustion, as delivered from the boiler, after passing through any economizer section or parts of the boiler and about to be delivered or discharged into the atmosphere, is, in part, transferred to a moving column of air, moving counter thereto, the air so heated being made available for various uses, as for instance, delivery to the combustion chamber of the boiler or to driers or to any other part of the factory or plant where heated air is used.

A further object of my invention is to provide a construction of air heater in which there is no banking of heat in any particular part of the heater but in which the transfer of heat from the hot gases to the air being heated is continuous throughout the passage of the gas and the air through the air heater.

A further object of my invention is to so arrange and dispose the parts of the heater that the temperature of the products of combustion at the time of their exit from the air heater to the atmosphere is lower than the temperature of the air discharged from the air heater, thereby making the transference of heat from the gases to the air continuous throughout the entire passage of the hot gases and air through the heater.

A further object of my invention is to provide a construction in which relatively thin layers of air are caused to freely flow throughout their travel through the heater between closely arranged banks of tubes through which the heated gases of combustion pass so that the air being heated is not substantially drawn transverse to the tubes but travels longitudinally of the tubes throughout substantially the entire length of the heated tubes.

A further object of my invention is to provide relatively large chambers at or near the ends of the banks of tubes, into which chambers the air being heated is discharged so that the air, being heated, may freely discharge therein from between the tubes

throughout the entire width of the bank of tubes.

Further objects of my invention will appear in the specification and claims below. 60

Referring now to the drawings in which the same reference characters are used to designate the same parts,

Fig. 1 is a side elevational view, partly in section, of the gas outlet end or side of the 65 apparatus.

Fig. 2 is a side elevational view of the gas inlet side of the apparatus.

Fig. 3 is a vertical longitudinal section taken on the line 3—3 of Fig. 1. 70

Fig. 4 is a vertical longitudinal section taken on the line 4—4 of Fig. 1.

Fig. 5 is a horizontal sectional view taken on the line 5—5 of Fig. 1.

Fig. 6 is a transverse horizontal sectional 75 view taken on the line 6—6 of Fig. 1.

Fig. 7 is a somewhat diagrammatic side elevational view illustrative of the manner in which the air heater is utilized.

My improved air heater preferably consists of a closure comprising a rectangular casing or housing 1 of boiler plate or similar sheet metal supported on any suitable framework 2 of structural iron or steel held elevated somewhat above the level of the cement or brick floor 3 by walls of brick or cement 4, one of which may be provided with a door or closure 5, to form a chamber Y below the casing or housing 1 for the collection of soot and similar solid products of 85 combustion which may accumulate therein by reason of the operation of the device and which may be removed therefrom from time to time through the door or opening 5.

The top wall 6 of the casing or housing is 90 imperforate. Spaced from the top wall 6 is a horizontal wall or partition 7 provided with a plurality of sets or groups a, b, c, d, e, f, of punched holes into which are expanded or otherwise fitted, the upper ends of 100 groups or banks A, B, C, D, E, F, of straight boiler tubes 8, the lower ends of which pass through and are similarly secured in similar groups or sets of holes, a', b', c', d', e', f' in the bottom tube plate 9 of the casing or housing 1.

The space between the upper or top wall 6 and the intermediate wall or tube plate 7 is divided by a vertical transverse partition 10 to form a gas inlet chamber X into which 110 the products of combustion from a boiler or heater are conducted by an inlet pipe 11 and

a gas outlet chamber Z from which the cooled gases of combustion are conducted by a suitable pipe 12 to the atmosphere. The flow of the products of combustion to, through and out of the heater may be effected by a suitable suction fan. Thus, the products of combustion will be drawn through the gas inlet pipe 11 into the chamber X and will be drawn or will pass downwardly through the tubes 8 of the banks of tubes A, B, C to the chamber Y formed by the bottom plate 9, the walls 4 and the flooring 3, and thence will pass upwardly through the tubes 8 of the banks of tubes D, E, F to the gas outlet chamber Z from which the cooled gases are conducted away through the gas outlet pipe 12. Between the banks of tubes A, B, C and the banks of tubes D, E, F, is a vertical dividing partition 13 of sheet iron extending from the under side of the top wall 6 downwardly but the lower edge of said partition 13 does not reach to the bottom wall or plate 9. It is spaced from the bottom wall or plate 9 to permit the air partially heated and consequently of greater volume than it was when introduced through the pipe to pass freely between the lower end of the plate or partition 13 and the bottom wall 9 of the housing. It may be well to state here that the air to be heated is conducted to my improved air heater through a substantially rectangular opening 14 through the rear end wall 16 immediately below the horizontal intermediate wall or tube plate 7 and preferably provided with vertical slots 30-31 opening into the spaces between banks D, E and F, respectively. The lower end of that part of the vertical partition 13 which is between the banks A and D, B and E, C and F is preferably spaced from the bottom plate or wall 9 a distance a little greater than the vertical height of the opening 14 to allow for the expansion of the air being heated and to provide a free passage through which it may pass without increasing its velocity.

On each side of the bank of tubes E and relatively close thereto and extending from the rear end wall 16 to the intermediate partition 13 are vertical partitions 17 and 18, the top edges of which are substantially on the level with the lower horizontal wall of the opening 14 and the lower ends of which are substantially on the level with the lower end of the vertical partition 13. Like and parallel partitions 19 and 20 enclose the banks D and F respectively from a point on the level with the lower side of the rectangular opening 14 to a point on the level with the lower end of the intermediate wall or vertical partition 13 so that each of the three banks of tubes D, E, F is enclosed on four sides for the greater portion of their length, the bank D by the side wall 21, the partitions 13 and 19 and the rear wall 16; the bank E by the partitions 17, 13 and 18 and the rear wall 16;

and the bank F by the partition 13, side wall 22, rear wall 16 and partition 20. The upper and lower ends of the said tubes, however, are not so enclosed but extend above and below the partitions.

Similarly, the bank of tubes B on the other side of the vertical partition 13 are enclosed between two vertical partitions 23 and 24, the partition 13 and the front wall 25, the tops of said partitions 23 and 24 being a little below the level of the tops of the partitions 17 and 18 and the lower edges of said partitions being substantially on the level of the lower edge of the vertical partition 13. Similar vertical partitions 26 and 27 are adjacent the banks A and C of tubes, the tops and bottoms of said partitions 26 and 27 being in the same plane as the tops and lower edges of the partitions 23 and 24 respectively. The bank of tubes A is enclosed for the greater portion of its length by the partitions 26 and 13, side wall 21, and front wall 25; and the bank C is similarly enclosed by the partitions 27 and 13, side wall 22, and front wall 25. In this way the three banks of tubes A, B, C are enclosed or encased for the greater portions of their entire lengths by casings formed by the vertical partition 13, the side walls 21 and 22 of the main casing 1, the front wall 25 and the vertical partitions 23, 24, 26 and 27.

Extending longitudinally of the casing 1 between the banks A-D, B-E and between the banks B-E and C-F respectively, and from the rear wall 16 to the front wall 25, and between the partitions 19-17 and 26-23, and between the partitions 18-20 and 24-27 respectively, are longitudinal partitions 28 and 29 sloping downwardly from the point where they intersect the dividing partition 13 to the point where they engage and are connected to the rear and front walls 16 and 25 respectively. The partition 13 is notched from its lower end upwardly to the points of its intersection with the partitions 28 and 29. Only between the banks of tubes A and D and the banks B and E and the banks C and F does the partition 13 extend below the partitions 28 and 29 as clearly shown in Figs. 3 and 4.

These partitions 28 and 29, coacting with the walls or partitions 17, 18, 19, 20, 23, 24, 26 and 27 and with the partition 13 and with the front wall 25 and the rear wall 16 and with the horizontal tube plates 7, form chambers G, H, I, J above the partitions 28 and 29 and below the tops of the partitions 17, 18, 19, 20, 23, 24, 26 and 27, namely, the chamber G between the banks D and E; the chamber H between the banks E and F; the chamber I between the banks A and B; and chamber J between the banks B and C.

Below the partitions 28 and 29 and above the lower ends of the walls or partitions 17, 18, 19, 20, 23, 24, 26 and 27, and coacting with the front and rear walls 25 and 16 respective-

ly and with the bottom plate 9, they form two relatively large chambers K and L extending the length of the interior of the casing as clearly shown in Figs. 1 and 4.

5 In the rear wall of the housing or casing 1 the two vertically disposed rectangular openings 30 and 31 extending from the lower edges of the air inlet opening 14 to the rear ends of the partitions 28 and 29 respectively, said 10 openings 30 and 31 are respectively in registration or alinement with the air inlet chambers G and H. These openings 30 and 31 are for the purpose of facilitating the ingress of air to the chambers G and H whence the 15 air may freely pass around the upper ends of all the tubes to the space between the tubes of the banks of tubes.

The front end wall 25 is provided with similar vertically extending slots or openings 34 and 35, similarly communicating with the air exit chambers I and J between the banks of tubes A—B and B—C. These openings 34 and 35 are enlargements of the air exit opening 36 and extend downwardly from 25 the lower edge of the air exit opening 36 to the front ends of the partitions 28 and 29. These openings 34 and 35 are preferably closed by hoods or conduits 37 and 38 forming branches of the air exhaust conduit 39 30 and also serve to form enlargements of the chambers I and J into which the air coming from between the banks of tubes A, B and C freely flows and circulates.

In Fig. 7 is illustrated, more or less diagrammatically, the manner in which my improved air heater may be operated.

The gas inlet pipe 11 is attached to the boiler 40 above and to the rear of the economizer 41, at the point where the products of 40 combustion are usually discharged to the stack, and to the gas outlet pipe 12 of the heater is attached a fan or blower 42 which, when operated, draws the products of combustion from the boiler 40 through the pipe 45 or conduit 11, through the heater, outlet pipe 12, fan 42 to conduit 43 which may lead to a stack or directly to the atmosphere.

The air outlet conduit 39 is attached to a fan or blower 44, operative to draw air into 50 the heater 1 by air inlet opening 14, thence through the heater to the pipe 39 and from the fan a pipe or conduit 45 may run to a point below the grate 46 of the boiler 40 to supply hot air to the fuel being consumed.

55 A branch pipe or conduit 47 may connect with the conduit 45 and lead to a drier or other apparatus requiring hot air.

The operation of my air heater is as follows: The products of combustion, (smoke and hot gases), as they leave a boiler 40 and as they are ordinarily discharged to the atmosphere, are drawn by a suitable suction fan 42 or an equivalent device through the hot gas inlet pipe 11 into the gas inlet chamber X whence they pass downwardly through

the tubes of the banks A, B, C into the chamber Y below the bottom tube plate 9 and here they sweep downwardly and rearwardly to the lower ends of the pipes 8 of the banks D, E and F, where they pass upwardly through 70 the pipes to the gas outlet chamber Z from which they are conducted by the pipe 12 to the pump or suction fan 42, whence they are discharged through conduit 43 to the stack or directly to the atmosphere. 75

The air to be heated may be similarly drawn by a suction fan, pump or draft appliance 44 in through the air inlet opening 14 into the space around the upper ends of the tubes 8 of the banks D, E and F. It fills 80 the chambers G, H and circulates therein freely so that from the air inlet chambers G, H, the air flows over the top edges of the partitions 17, 18, 19 and 20 into the spaces between the pipes 8 of the banks of pipes D, 85 E, F. In this way the air is given an opportunity to freely enter the narrow spaces between the pipes directly from the air inlet chambers G, H and to travel downwardly lengthwise of the pipes 8, on the outside of 90 them, for substantially the full length of the pipes 8. The air flows freely from between the pipes 8 into relatively large chambers K, L which greatly augment the passage between the front and back banks below the 95 partition 13, so that the air being heated enters these chambers from all the spaces between the tubes of banks D, E, F. From these chambers K, L it is again gently drawn downwardly and in between the narrow spaces between the tubes 8 of the banks of tubes A, B, 100 C where it is caused to travel upwardly over the tubes 8 for substantially the full length of the tubes 8. Over the tops of the partitions 23, 24, 26 and 27 the air readily passes into 105 and fills the air exit chambers I, J above the partitions 28 and 29, from which and from between the upper ends of the pipes 8 it is conducted through the air exhaust pipe 39 and its hoods 37, 38 by the fan 44 and conduit 110 45 to a suitable point below the grate 46 where it is discharged. Or a part 7 of the heated air may be conducted by pipe 47 to some other place in the plant where hot air is needed. By virtue of this arrangement the 115 air being heated is practically introduced into a large chamber in communication with the top ends of the banks of tubes D, E and F. It is then caused to traverse the entire length of the tubes in the banks D, E, and F 120 and then thus therefrom into a relatively large chamber around the lower ends of the tubes of the banks D, E, and F. From this last-mentioned chamber the air is drawn upwardly between the tubes of the banks A, B 125 and C and is discharged at the upper end thereof into a substantially large chamber surrounding the upper ends of the tubes of banks A, B and C.

In this way every part of the air being 130

heated is caused to travel substantially the entire length of the outside of the pipes 8 of the banks A, B, C, D, E, F of hot tubes, through narrow spaces between the tubes, and 5 without very much transverse movement with respect to the pipes. Every part of air is brought into close relationship with the heated pipes and is caused to travel first downwardly and then upwardly a distance sub-

stantially equal to twice the length of a single tube 8. It is very essential that the tubes of the banks of tubes should be closely arranged with respect to each other so that the air passing between the pipes is substantially in thin 10 layers which are more readily heated than are thick layers of air.

As a practical illustration of the way in which my improved air heater is operated, I may take the products of combustion (hot 20 gases and smoke) at say 425° F., and reduce the temperature of such products of combustion down to 140° F. In so doing I am able to raise the temperature of the air entering the heater at a temperature of say 70° 25 up to a temperature of 150°. When the air so heated is delivered to the fire-box or combustion chamber of the boiler or heater 40 the heat that would have otherwise been lost is returned to the boiler with a consequent increase 30 in the efficiency of the operation of the boiler. All or a part of the air may be taken to a drying room or other place where hot air is required and there utilized, thereby effecting a saving of the cost of heating the 35 air for such uses in any other manner. In so doing it will be noted that at any point in the air heater the temperature of the gas in the tube at that point is substantially higher than that outside of the tube at that point. Throughout 40 the apparatus the gases are practically meeting a counterflow of air being heated and the air is practically meeting a counterflow of hot gases. At any point in the heater there is a substantial difference 45 between the temperature of the air and that of the gases. The gases are always hotter than the air at any given point and the air is always cooler than the gases at any given point. This insures a continual transfer of 50 heat from the hot gases to the air throughout their passage through the heater so long as the temperature of the gas leaving the heater is higher than the temperature of the air entering the heater.

55 The construction and the operation of an apparatus embodying my invention has thus been described above, but it is to be understood that the details of construction might and naturally would be changed or altered 60 to adapt the heater to different boilers or heaters operating under different conditions and where the air to be heated is required to be raised to different temperatures, but in such constructions, the air to be heated will 65 be conducted as a counterflow over and be-

tween tubes through which the products of combustion are being conveyed in the opposite direction and in the manner above described, each particle of air will be brought into close association with the heated products and will be caused to travel substantially the entire length of the tubing through which the products of combustion are being conducted.

Having thus described my invention, what 75 I claim and desire to protect by Letters Patent of the United States, is:

1. An air heater comprising a gas inlet chamber, a gas outlet chamber, an intermediate gas chamber spaced from said gas inlet and gas outlet chambers, two spaced banks of tubes connecting said gas inlet chamber with said intermediate gas chamber, two spaced banks of tubes connecting said intermediate gas chamber with said gas outlet chamber, partitions within said casing and forming with said casing an air inlet chamber adjacent said gas outlet chamber, forming an air outlet chamber adjacent said gas inlet chamber and forming an intermediate air chamber between said air inlet and air outlet chambers on the one hand and said intermediate gas chamber on the other hand, said air inlet chamber being between said two banks of tubes which are connected with said gas outlet chamber and communicating with the spaces between said tubes at the ends thereof which are connected to said gas outlet chamber; said air outlet chamber being between said two banks of tubes which are connected with said gas inlet chamber and communicating with the spaces between said tubes at the ends thereof which are connected to said gas inlet chamber; and said intermediate air chamber being in communication with the spaces between all of said banks of tubes at the ends thereof which are connected to said intermediate gas chamber.

2. An air heater comprising a closure having therein a gas inlet chamber, a gas outlet chamber and an intermediate gas chamber, a plurality of spaced banks of closely parallel tubes connecting said gas inlet chamber with said intermediate gas chamber, a plurality of spaced banks of closely disposed parallel tubes connecting said intermediate gas chamber with said gas outlet chamber, an air inlet chamber between said banks of tubes and adjacent said gas outlet chamber, an air outlet chamber between said banks of tubes and adjacent said gas inlet chamber, and relatively large intermediate air chamber, partitions in said casing parallel to said tubes and forming with the casing closures 110 surrounding each bank of tubes for the major portion of the length of said tubes, said partitions dividing said gas inlet from said gas outlet chamber and said air inlet chamber from said air outlet chamber and a lon- 115 120 125 130

- 5 gitudinal partition in the space between said banks and intermediate the ends of said partitions, dividing the intermediate air chamber from said air inlet chamber and from 5 said air outlet chamber, and means for drawing air into said air inlet chamber and thence over substantially the entire length of the outer surfaces of said tubes connecting said gas outlet chamber with said intermediate 10 gas chamber, and thence into said intermediate air chamber, and thence substantially over the entire length of the outer surface of the tubes connecting said gas inlet chamber with said intermediate gas chamber and 15 thence into said air outlet chamber whereby the air travels relatively rapidly over substantially the entire length of the outer surface of said tubes in a direction counter to that of the gases of combustion passing 20 through said tubes and relatively slowly through said intermediate air chamber.
3. An air heater comprising a closure having a gas inlet chamber therein adjacent a side of said closure, an intermediate gas 25 chamber extending substantially the entire length of said closure adjacent the opposite side of said closure, a gas outlet chamber adjacent said first mentioned side of said closure, the combined length of said gas inlet 30 and of said gas outlet chambers being together substantially the length of the closure, a group of spaced banks of closely arranged parallel tubes connected at one end with said gas inlet chamber and at their other ends with 35 said intermediate gas chamber, a second group of spaced banks of closely arranged parallel tubes connected at one end with said intermediate gas chamber and at their other ends with said gas outlet chamber, a dividing 40 partition between said groups of spaced banks of tubes, partitions parallel to said tubes and between said banks and cooperating with the walls of said closure and with said dividing partition to surround the greater portion of the length of said tubes of each bank, said tubes extending beyond the ends 45 of said parallel partitions, said closure being also provided with a longitudinal partition extending the full length of said closure and located between said banks, intermediate the ends of said parallel partitions, said closure being 50 also provided with a longitudinal partition extending the full length of said closure and located between said banks, intermediate the ends of said parallel partitions surrounding said banks and forming an air inlet chamber between said longitudinal partition and said gas outlet chamber communicating with the 55 spaces between the tubes at the ends thereof which are connected to the gas outlet chamber; forming a relatively large intermediate air chamber between said longitudinal partition and said intermediate gas chamber, in free communication with the spaces between 60 all of said tubes at the ends thereof which are connected to said intermediate gas chamber; and forming an air outlet chamber between said longitudinal partition and said gas inlet chamber and communicating with the space 65 between the tubes at the ends thereof communicating with said gas inlet chamber.
4. An air heater comprising a closure having a gas inlet chamber therein adjacent the top side of said closure, an intermediate gas 70 chamber extending substantially the length of said closure adjacent the bottom side of said closure, a gas outlet chamber adjacent the top side of said closure, the combined length of said gas inlet and outlet chambers 75 being substantially the length of said closure, a group of spaced banks of closely arranged parallel tubes connected at their upper ends with said gas inlet chamber and at their lower ends with said intermediate gas chamber, a second group of spaced banks of closely arranged parallel vertical tubes connected at their lower ends with said intermediate gas chamber and at their upper ends with said gas outlet chamber, a vertical dividing partition between said groups of banks, partitions parallel to said tubes between said banks and co-operating with the walls of said closure and with said vertical dividing partition to surround the greater portion of the lengths of 80 the tubes of each bank, said tubes extending above and below said parallel partitions, said closure being also provided with a longitudinal partition extending for the full length of said closure and located between said banks 85 intermediate the ends of said parallel partitions surrounding said tubes, said longitudinal partition co-operating with said vertical dividing partition to form an air inlet chamber below said gas outlet chamber communicating with the spaces between the upper ends of the tubes which are connected with said gas outlet chamber; said longitudinal partition forming a relatively large intermediate air chamber between said longitudinal partition and said intermediate gas chamber in communication with the space between all of the tubes at the lower ends thereof; said longitudinal partition forming, with said vertical partition an air outlet chamber below said gas 90 inlet chamber and communicating with the space between the upper ends of the tubes which are connected with said gas inlet chamber.
- 45 In witness whereof I have hereunto set my hand this fourth day of December, 1925.
- 50 JOSIAH H. ROHRER.
